UNITED STATES PATENT OFFICE

2,463,281

DUAL TURRET CONVEYER

Thomas M. Kane, Baltimore, Md.

Application January 8, 1947, Serial No. 720,862

2 Claims. (Cl. 101—36)

1

This invention relates to conveying equipment and more particularly to such having a composite function coordinated with its mechanism for treating the articles or items conveyed so they will be actuated or formed in some particular manner to produce a differentiated product from that originally conveyed.

The conventional type of conveyor is designed to carry material from one location where it is received to another where it is delivered, taking no part in producing or changing the physical nature of the product. In other words its principal and only object is to transport the items mechanically and avoid the use of human labor for the purpose. The arrangement is based on the fact that the work can be done by the conveyor, continuously, more quickly, uniformly, and economically by such means than by labor. The purpose of this invention is to increase the efficiency of the conveyor by utilizing the period of time required for the conveyance of a manufactured product between two points, as an occasion to produce a commercial change in the product so that its resulting value will be greater than it was when it started on the conveyor and time otherwise wasted will be put to practical use. This is accomplished by including additional mechanism that can operate on the items conveyed while being carried without interfering with the regular routine of its time of travel, but performing some function that adds to the degree of finish given the product or items. This mechanism is coordinated with the operation of the conveyor to work cooperatively therewith.

It is an object of the present invention to provide a new and improved conveyor mechanism that will avoid one or more of the disadvantages and limitations of the prior art.

A further object of the invention is to provide a new and improved conveyor equipment that will be capable of treating the items conveyed, as they are so carried, so their finish or commercial utility will be augmented.

An additional object of the herein described invention is to provide a new and improved conveyor equipment that will facilitate the process of production in addition to transporting the items concerned from one location to another, and perform the functions desired during the period of such transportation.

These and further objects will be rendered apparent as the invention is further detailed.

For a better understanding of the invention, reference is made to the appended drawings and the description following, which together outline

2

a particular form selected in this instance to illustrate the invention and indicate the principles on which it is based, while the scope of the invention will be particularly pointed out in the claims.

The particular form of the construction used in the drawings is designated in the various details in which,

Figure 1 is a plan view of a composite conveyor and process mechanism embodying this invention;

Figure 2 is a sectional elevation taken along the longitudinal center line of Figure 1;

Figure 3 is a sectional view taken along line 3—3 of Figure 1, showing the detail of the cam mechanism used for processing in this invention;

Figure 4 is a sectional view taken along line 4—4 of Figure 2, of a detail of the carrier used in this embodiment;

Figure 5 is a sectional plan view taken along line 5—5 of Figure 2, and

Figure 6 is an end view of the carrier looking in the direction of the arrows 6—6 of Figure 3.

Similar reference characters refer to similar parts throughout the drawings.

In the construction shown, a table 10 is used for the support of the mechanism, and is in turn supported on suitable standards 11 resting on the floor. The table 10 is holed at 12 to permit the passage of a shaft 14 therethrough. The shaft 14 is held vertically in place on the table by a plate 16 attached to the underside of the table 10 by bolts 15. A miter gear 17 is secured to the end of the shaft 14 and meshes with another miter gear 18 attached to a shaft 19 journalled in one of the standards 11. A pulley 20 or other type of transmission unit is mounted on the end of the shaft 19 to enable it to be operated by an extraneous motor or other source of power. This shaft 19 is restricted laterally by a flange plate 21 bolted to the standard in question. The shaft 14 is keyed to a toothed or slotted wheel 24 and held at a predetermined height above the table and forming the driver for a conveyor belt 25. This belt 25 goes around the periphery of the driver 24 and travels continuously in either direction on same. It carries rectangular turrets 26 which are slidably fastened to bent flanges 27 which are attached to the belt 25 on one side while an angle 28 is fastened to the outside of the belt by bolts 29. The turrets through the bent flanges and angles slide along rails 35 positioned on supports 39 mounted on table 10. These turrets 26 have toothed or concave projections 13 that engage in slots 30 in the

50 55

driver 24 as the latter rotates. The turrets are so spaced, that they contact the driver every 90° or on each quadrant. They are reciprocated up and down by a plunger 32 which reciprocates in openings 31 provided in the driver structure 24, so that the plungers 32 can operate therethrough when their wheel end contacts one or more portions of the cam elements 34 in the proper sequence. The plungers are loosely held in the driver structure 24 and their upper end portions contact springs 23 attached to plugs 22 and force the rectangular turrets 26 upwardly for performing the stamping or forming operations designed for them, on the article being conveyed. Normally the plungers are in their lowest position within openings 31 in the driver 24, and they are raised when they reach the cam elements 34 mounted on the upper surface of the table 10 at predetermined or suitable locations. An idler wheel 124 mounted on an idler shaft 114 serves to carry the conveyor belt 25 over the further end of the table and its travel. It is provided with slots 130 to enable it to engage the projections 13 as they pass along. The shaft 114 is of a stub type held on the table 10 by a sleeve 40 which slides in a dove tail slot 41 in the table and is adjusted by a screw 42 to tighten the conveyor belt 25. The cam 134 is similar to 34, the plungers 132 are similar to 32 the plugs 122 are similar to 22 and they operate similarly. The engagement of the teeth 13 in the recesses as each turret comes around causes the turrets to align as they pass by the place of engagement in accurate relationship. As the cam element coincides with the plunger at this location, it makes the operation of the plunger follow at the proper instant. The articles carried by the turrets are held by upright pins 44 suitably arranged around them so as to locate them over the respective plunger. The cam element on engaging with the plunger and wheel under the article on that particular turret will raise the plunger so the article will be brought against tools 45 and 145 mounted on the upper portion of the shafts 14 and 114 and mark or form it as required. Since the tools are mounted on the shafts 14 and 114 it will be evident that the tools rotate at the same speed as the turrets and that, consequently, the articles carried thereby will be stamped without blurring or smudging when the tools and the articles are in alignment as shown in Figure 2 of the drawings. The tool shown for the purpose of illustration consists of an embossing stamp 46 and the manufactured article 47 that is impressed with a mark by the stamp when the plungers 32 and 132 forcibly raises the article against it is shown at 41.

In the particular form illustrated, the arrangement is such that six cam elements may be used and a similar number of tools used to produce their respective effects on the articles. It will be understood, however, that any other arrangement may be used if found desirable or necessary. The cam elements have their faces contoured to

suit the particular function required of them and are established solidly on the table at the locations selected and operate the plungers without requiring the conveyor belt to stop or change its speed during the operation or in fact interfere with the regular operation of the conveyor.

The operation of the device follows from the pulley 20 through the shaft 19, gears 18 and 17 to the shaft 14, which in turn rotates the wheel 24, and causes the belt 25 to travel with the latter and in turn revolve the wheel 124.

As the articles 47 are carried on the turrets 26 by the belt 25 to the wheels 24 and 124, over the plungers 32 and 132, they are lifted at quadrants where the cam elements 34 are situated and lifted into contact with the stamp or tool 45, then lowered and brought to the next step. The method of removal of the articles and their placement on the turrets may be in any conventional manner depending on the product in question. In the present instance, this is done by hand and the table 10 is used as a temporary resting place, or for conveniently storing a few at a time.

Having thus described the invention, what is claimed is:

1. In a marking apparatus, a supporting table, a plurality of spaced shafts extending through said table, a driving element rotatably mounted on one of said shafts, a driven element rotatably mounted on the other shaft, an endless conveyor belt connecting said elements, mark-forming tools carried by and rotating with said shaft in a plane parallel to said elements, spaced work supporting members secured to said belt in a plane parallel with and between the respective elements and mark-forming tools, a plurality of reciprocable plungers mounted in the driving and driven element, and cam means on the table adjacent the respective elements and adapted to cooperate with said plungers for raising the plungers above the plane of the respective elements to raise the work on the work supporting members into contact with the tools.

2. A marking apparatus as set forth in claim 1, said conveyor belt having a plurality of spaced-apart teeth and said driving and driven elements having spaced recesses adapted to cooperate with said teeth.
